VIEWER FOR STEREOSCOPIC PICTURES

Charles C. Ripley, Pasadena, Calif., assignor to Hycon
Mfg. Company, Pasadena, Calif., a corporation of
Delaware

Application September 14, 1954, Serial No. 32,291

Term of patent 14 years

(Cl. D61—1)

Fig. 2.

Fig. 1.

To all whom it may concern:

Be it known that I, Charles C. Ripley, have invented a new, original, and ornamental Design for Viewer for Stereoscopic Pictures, of which the following is a specification, reference being had to the accompanying drawing, forming a part hereof.

Fig. 1 is a perspective view of the top of a viewer for stereoscopic pictures showing my new design.

Fig. 2 is a perspective view of the bottom of the viewer for stereoscopic pictures.

I claim:

The ornamental design for a viewer for stereoscopic pictures, as shown.
